UNITED STATES PATENT OFFICE

2,464,800

PORTABLE TUBE BENDING TOOL

George E. Franck, Riverside, Ill., assignor to The Imperial Brass Manufacturing Company, Chicago, Ill., a corporation of Illinois

Application July 15, 1944, Serial No. 545,095

3 Claims. (Cl. 81—15)

1

My invention relates to a hand service tool and particularly a tool for bending tubing. The invention has great utility in the bending of thin-walled metal tubing made of such materials as copper, brass and aluminum.

Among the objects of my invention is to provide a new and improved bending tool for tubing in which all of the parts are permanently attached together so that they cannot inadvertently be separated one from another.

Another object of my invention is to provide a new and improved bending tool for tubing which is compact in its construction by reason of the elimination of excess parts and which is efficiently designed from the point of view of operation.

Still another object of my invention is to provide a new and improved bending tool consisting of two parts loosely attached together so that they can be opened up for reception of tubing without being completely separated one from the other and which can then be engaged in a bending position with respect to each other and the tubing for performing the necessary bending operation; there being included also among the objects the provision of a bending tool which can be released from the tubing at any point in the bending operation.

Among the further objects of my invention is to provide a bending tool including lever arms which can be released from the tubing at any point in the bending operation.

Among the further objects of my invention is to provide a bending tool including lever arms which are grasped by hand for making the bend wherein the lever arms at the start of the bend are extended one with relationship to the other in the most appropriate position for exerting proper leverage and control over the tool and in such a manner that effective leverage and control is maintained throughout all positions during the making of a bend of 180°.

A further object also of my invention is to provide a bending tool comprising two parts permanently attached together but which can be released a limited extent for reception of the tubing and then engaged in tube-bending relationship wherein the connecting means between the two parts is so arranged that the pressure exerted during the bending operation tends to hold the parts more tightly in proper bending relationship.

With these and other objects in view, my invention consists in the construction, arrangement and combination of the various parts of my de-

2

vice whereby the objects contemplated are attained, as hereinafter more fully set forth, pointed out in my claims and illustrated in the accompanying drawings, in which:

- 5 Figure 1 is a side view of the bending tool with the ends of the bending levers broken away showing in solid lines the tool and a tube engaged as for starting a bend and in dotted lines the position of the bending levers separated a limited extent for reception of a tube.
- 10 Figure 2 is a side view of the reverse side of Figure 1.
- 15 Figure 3 is an end view taken on the line 3—3 of Figure 1.
- 15 Figure 4 shows the relative position of the parts of the tool at the completion of a 90° bend.
- 20 Figure 5 shows the parts of the tool to a smaller scale in the position occupied at completion of a 180° bend.
- 25 In the bending of thin-walled tubing for ordinary commercial purposes such as for installation of refrigeration lines and for fuel and oil lines in automobiles and aircraft it is necessary to employ a bending tool which is convenient and compactly arranged and at the same time one which can successfully bend thin-walled tubing without crushing the tubing or distorting it unduly in its cross-sectional shape. Pipe benders of a wide variety have been devised in the past
- 30 but these for the most part are bending tools not meant to be carried around in a service kit. There have likewise been tools directed primarily to the purpose of bending hard-walled pipe and they have failed to have incorporated in them the requirements necessary to prevent a bending tool from distorting and crushing relatively soft thin-walled tubing. Some few bending tools have been devised for bending tubing but those which have been available heretofore have lacked the simplicity and convenience needed in a tool which can be readily carried about in a service kit and quickly put to use by mechanics with limited skill, especially in relatively inaccessible corners where machinery has to be installed.
- 35 In the drawings there is shown a bending block 10 about which the tube is to be bent. This block is in the form of a substantially circular disc of appreciable thickness which has a semi-circular groove 12 having a diameter equal to the size
- 40 of the tubing to be bent extending around the edge of the bending block. There is a flat surface 14 on one side of the bending block and a handle 16 threadedly engages the bending block at the flat side. A clamp 18 for holding a length
- 45 of tubing 20 is mounted rotatably upon the handle
- 50
- 55

16 at a point immediately adjacent the bending block and is held in this position by a shoulder 17 on the handle. The clamp has a somewhat hook-shaped slot 22 as best seen in Figure 3, and may be mounted to rotate axially about the handle. The surface of the hook which engages the tubing is relatively long so that pressure developed during the bending operation will not mar or dent the portion of the tube engaged by the clamp.

Cooperable with the bending block and handle is a bending lever 26 which has a relatively large streamlined head 28 provided with a flat side piece 30 which lies flat against the rear face of the bending block as viewed in Figure 1. The flat side piece is held rotatably against the bending block by means of the large head 32 of a shaft 34 which is centrally disposed relative to the bending block. As shown in Figure 3 the shaft 34 is riveted over in order to permanently secure it in fixed position upon the bending block.

The bending lever 26 is provided with a forming element 36 having therein an elongated semi-circular groove 38 having substantially the same cross-sectional diameter as the groove 12 in the edge of the bending block.

In the flat side piece there is provided an arcuate slot 40 terminating in rounded ends 40' and 40'' of a radius just slightly larger than that of the shaft 34. The balance of the slot is of a uniform width slightly greater than the diameter of the shaft 34 so that the shaft may slide freely from one end of the slot to the other while held therein by the head 32. While the slot 40 is here shown as arcuate, which is a preferred form, it need not take that precise form so long as the halves of the slot are disposed at an angle to one another.

The position of the slot 40 relative to the forming element 36 is such that when the shaft 34 is in the end 40' the edges of the forming element 36 just clear the periphery of the block 10. The end 40'' of the slot is located beyond the end 40' in an obliquely forward direction. By forward direction is here meant from the handle portion of the lever 26 toward the head 28. Thus the slot 40 extends generally in the same direction that the head extends from the handle portion of the lever 26 and with the side of larger radius nearer the groove 38. With this mode of coupling, the cooperating elements are separated for reception or discharge of a piece of tubing by relative generally longitudinal movement of the lever 26, and are returned to operative bending position by similar movement in the opposite direction. Only a slight movement of a fraction of an inch is necessary and no swinging of the lever 26 is required to receive or discharge a piece of tubing, and this is true regardless of the relative angular positions of the members 16 and 26.

About the exposed face of the bending block a series of numerals show intervals from 0 to 180 and are cooperable with an indicating mark 42, so that the coinciding of the indicating mark with one of the numerals will immediately show the extent to which the tube has been bent. See for example Figure 4 where the tube has been bent through an angle of 90°.

In operation the parts of the tube-bending tool are initially separated one with respect to the other, as shown in Figure 1 by the handle and bending block in solid lines and the bending lever in dotted lines. The shaft 34 is now in the end 40'' of the slot. Where the parts of the bending tool are separated to this extent there is sufficient room between the edge of the forming element

36 and the edge of the bending block 10 so that the tube can be inserted by lateral movement between them and thereafter be positioned within the groove 12 and the bending block. After the tube has thus been inserted the clamp 18 can be pivoted about until the hooked portion engages the tube 20, as best shown in Figure 3. Note that the side piece 30 now lies on one side of the tubing and the clamp 18 on the other side.

10 After the tube has thus been hooked in place the bending lever is moved into bending relationship with the bending block. This is accomplished by means of sliding the bending lever together with the flat side piece in a direction toward the bending block so that the shaft 34 slides from the end 40'' of the slot 40 to the end 40' of the slot. When the shaft 34 has finally been received into the end 40' of the slot as just described, the bending lever 26 is then pressed into bending relationship so that the forming element 36 bears against the tubing and at the same time presses the end wall of the slot against the shaft. By reason of the pressure acting in this way the tendency of the pressure exerted during the bending operation is to always press and maintain parts of the tool in bending relationship with the tubing.

20 As the bend continues to be made by rotating one handle about the other, the bend progresses as illustrated in Figure 4. This may extend to a 90° bend for example. If it is only a 90° bend which is desired the parts of the tool can be released by merely relieving the pressure upon the handle at that point and thereby permitting 30 the shaft to slide from the end 40' of the slot shown in Figure 4 to the end 40'' of the slot. This movement will separate the parts of the tool sufficiently so that the clamp can be removed and the tube extracted laterally from the tool.

35 40 Should a 180° bend be required the parts of the tool are rotated until they assume the relative positions shown in Figure 5. From this position also the parts of the tool are released in a manner similar to that described in Figure 4 and the tube released as previously described.

45 There has thus been provided a convenient and compact bending tool all in one piece which can be readily carried about in a serviceman's kit and which is capable of making bends in tubing to 50 any degree between 0 and 180°, and which can be readily released from the tubing at any degree of the bend.

55 Some changes may be made in the construction and arrangement of the parts of my device without departing from the real spirit and purpose of my invention, and it is my intention to cover by my claims any modified forms of structure, or use of mechanical equivalents, which may be reasonably included within their scope.

60 I claim as my invention:

1. A bending tool for tubing comprising a relatively stationary member including a bending block having a semi-circular grooved edge into which the tubing is bent, a handle extending from one side of the block and a rotatably mounted clamp for the tubing adapted to be swung into place over the tubing, and a relatively movable member including a bending lever having a handle, a flat extension on the lever on one side of the block having therein an arcuate slot rounded at its ends and of uniform width intermediate the rounded ends, means engaging the outside of the flat extension including a shaft at the center of curvature of the block extending 70 beyond one side thereof and laterally through

the arcuate slot and a forming element having a straight groove therein complementary in cross section to the groove in the block, said bending lever having an initial position wherein the forming element is separated from the block a distance sufficient to permit insertion of a piece of tubing therebetween when the shaft is in one end of the arcuate slot and having a bending position with the respective grooves closely surrounding the tubing when the shaft is in the other end of the arcuate slot, the last named end of the slot being inclined so that the center line thereof forms more than a 90° angle with a radial line perpendicular to the axis of the groove in the forming element, commencing with the radial line and measured in the direction of rotation of said forming element, to form a seat for said shaft during the bending operation.

2. A bending tool for tubing comprising a relatively stationary member including a bending block having a semicircular grooved edge into which the tubing is bent, a handle extending from one side of the block and a rotatably mounted clamp for the tubing adapted to be swung into place over the tubing, and a relatively movable member including a bending lever having a handle, a flat extension on the lever on one side of the block having therein an arcuate slot rounded at its ends and of uniform width intermediate the rounded ends, means engaging the outside of the flat extension including a shaft at the center of curvature of the block extending beyond one side thereof and laterally through the arcuate slot and a forming element having a straight groove therein complementary in cross-section to the groove in the block, said bending lever having an initial position wherein the forming element is separated from the block a distance sufficient to permit insertion of a piece of tubing therebetween when the shaft is in one end of the arcuate slot and having a bending position with the respective grooves closely surrounding the tubing when the shaft is in the other end of the arcuate slot, the last named end of said slot being inclined so that the center line thereof forms more than a 90° angle with a radial line perpendicular to the axis of the groove in the forming element, commencing with the radial line and measured in the direction of rotation of said forming element, and the first named end of said slot being inclined so that the center line thereof approaches parallelism with the radial line perpendicular to the axis of the groove in the forming element.

3. A bending tool for tubing comprising a relatively stationary member including a bending block having a semicircular grooved edge into which the tubing is bent, a handle extending from one side of the block and a rotatably mounted clamp for the tubing adapted to be swung into place over the tube, and a relatively movable member including a bending lever having a handle, a flat extension on the lever on one side of the block having therein an arcuate slot rounded at its ends and of uniform width intermediate the rounded ends, means engaging the outside of the flat extension including a shaft at the center of curvature of the block extending beyond one side thereof and laterally through the arcuate slot and a forming element having a straight groove therein complementary in cross-section to the groove in the block, said bending lever having an initial position wherein the forming element is separated from the block a distance sufficient to permit insertion of a piece of tubing therebetween when the shaft is in one end of the arcuate slot and having a bending position with the respective grooves closely surrounding the tubing when the shaft is in the other end of the arcuate slot, the last named end of said slot being inclined so that the center line thereof forms more than a 90° angle with a radial line perpendicular to the axis of the groove in the forming element, commencing with the radial line and measured in the direction of rotation of said forming element, and the first named end of said slot being inclined so that the center line thereof approaches parallelism with the radial line perpendicular to the axis of the groove in the forming element.
